UNITED STATES PATENT OFFICE.

EUGENE VICTOR GRATZE, OF LEYTONSTONE, ENGLAND.

INSTRUMENT FOR INDICATING SPEEDS, DISTANCES COVERED, AND THE LIKE.

No. 877,711.

Specification of Letters Patent.

Patented Jan. 28, 1908.

Application filed October 16, 1906. Serial No. 339,221.

To all whom it may concern:

Be it known that I, EUGENE VICTOR GRATZE, a subject of the King of Great Britain, and a resident of "Woodhayne," 1 Maple road, Leytonstone, Essex, England, have invented a new and useful Instrument for Indicating Speeds, Distances Covered, and the Like, of which the following is the specification.

10 This invention relates to improvements in instruments for indicating speeds and distances covered. It may indicate the number of revolutions per minute, or it may record the distance traveled. It may be connected to the shaft of any rotary machinery, or to motor-driven vehicles or the like.

The deflection of the indicating movement in prior indicators of this type has been effected by revolving a magnet or magnets 20 round a central core and conductor, or by revolving a conductor round a central core of conducting metal placed near or between the poles of a magnet. In the former case, the magnets exert a drag on the conductor, 25 which deflects to a distance proportional to the speed. In the latter case, the conductor revolves round the central core, upon which it exerts a drag, proportional to its speed and also to the number of magnetic lines it 30 cuts per unit of time.

The action of this apparatus depends upon a revolving conducting armature or core (inside a metallic cylinder or case) turning between the poles of a permanent magnet. 35 This magnet is stationary and made in circular form, the pole pieces being semi-circular and just large enough to contain (between their faces) the armature and metal cylinder or case, in such a manner that the latter may both turn freely. The walls of 40 the conducting cylinder or indicating movement are very thin. Therefore the air gaps between the magnet poles and the armature or core are reduced to a minimum and do not offer much resistance to the lines of force. In addition, the movement is of a maximum lightness.

The magnet has practically a closed circuit, so that it is able to retain its full 50 strength for an unlimited time. Moreover, as the magnet does not revolve, it is not affected by vibration or external fields. Also, as it is almost a complete circle, it may be made comparatively smaller to retain a 55 greater strength of magnetism than would

otherwise be the case. The armature or core revolves, and, being constructed of conducting metal, induces the lines of force through the walls of the metal cylinder or case within which it turns, thereby creating 60 eddy currents and exerting a drag upon it.

The invention is illustrated by the accompanying drawings, in which—

Figure 1 is an elevation of the internal mechanism with the dial removed, Fig. 2 is a vertical section of Fig. 1, Fig. 3 is a horizontal section of Fig. 1; showing the mechanism with part of the cover, dial, magnet, base and movement cut away.

M is a permanent magnet; placed centrally between the poles of the magnet is a conducting armature or core A, which revolves round a spindle S. In this latter is set a jewel J. The metal cylinder or case C, is suspended or balanced between the jewels J and J'. This allows the walls of the metal cylinder C to turn freely in the gaps left between the two magnet poles and the edges of the conducting core or armature A. The driving medium is attached to the spindle B, thereby transmitting the motion to the spur wheel W through the medium of the spur wheel W, as shown in Fig. 2. The spur wheel W is fixed to the armature A by a metal collar D. The armature A, revolving inside the cylinder or case C, tends to drag the latter round with it, but this pull or drag is controlled by a spring N, which limits the deflection and causes same to become proportional to the speed of the armature. Therefore, as the speed of the 90 armature or core A increases, the deflection of the case C increases also, this deflection being calibrated off on a suitable scale in miles per hour, revolutions per minute or any other quantity requiring to be indicated.

The register R is driven by a worm T through the medium of a suitable toothed wheel O. The mechanism is mounted on a suitable base E, contained in a case or cover F, and the indicating hand moves over a scale 100 fixed to a dial G. A clamp H is mechanically operated to clamp or clutch the movement P, should it be desired to hold the latter in any temporary fixed position. K is a suitable glass set in the cover.

What I claim as my invention and desire to secure by Letters Patent is:—

1. In combination, a substantially annular stationary magnet, a revolving core positioned between the poles of the magnet, a

105

110

metallic casing adapted to embrace the core and extending beyond both sides thereof, spring means for controlling the rotation of the casing, indicating means operated by the 10
5. casing, and means for rotating the core.

2. In combination, a stationary magnet substantially annular having concaved terminals positioned between the terminals of the magnet, a metallic casing embracing the

core, and indicating means operated by the 10
casing.

In testimony whereof I have signed my name to this specification in the presence of the two subscribing witnesses.

EUGENE VICTOR GRATZE.
